UNITED STATES PATENT OFFICE

135,595

DESIGN FOR A CERAMIC BROOCH PIN

Elliot Handler, Los Angeles, Calif.

Application March 29, 1943, Serial No. 109,835

Term of patent 3½ years

To all whom it may concern:

Be it known that I, Elliot Handler, a citizen of the United States of America, residing in Los Angeles, county of Los Angeles, and State of California, have invented a new, original, and ornamental Design for a Ceramic Brooch Pin, of which the following is a specification, reference being had to the accompanying drawing, forming part thereof.

Fig. 1 is a plan view of a ceramic brooch pin showing my new design.

Fig. 2 is an edge view thereof.

I claim:

The ornamental design for a ceramic brooch pin, substantially as shown.

ELLIOT HANDLER.
